CLAIM

The ornamental design for an extracorporeal blood processing apparatus, as shown and described.

DESCRIPTION

FIG. 1 is a perspective view of one embodiment of an extracorporeal blood processing apparatus of the claimed design; FIG. 2 is a front view of the apparatus of FIG. 1; FIG. 3 is a rear view of the apparatus of FIG. 1; FIG. 4 is a left side view of the apparatus of FIG. 1, the right side view being a mirror image of the left side view; FIG. 5 is a top view of the apparatus of FIG. 1; FIG. 6 is a perspective view of another embodiment of an extracorporeal blood processing apparatus of the claimed design; FIG. 7 is a front view of the apparatus of FIG. 6; FIG. 8 is a rear view of the apparatus of FIG. 6; FIG. 9 is a left side view of the apparatus of FIG. 6; FIG. 10 is a right side view of the apparatus of FIG. 6; and, FIG. 11 is a top view of the apparatus of FIG. 6. The broken lines in the figures do not form a part of the claimed design.

1 Claim, 11 Drawing Sheets
